UNITED STATES PATENT OFFICE.

JOHN REAM, OF JACKSONVILLE, FLORIDA.

DREDGING APPARATUS.

1,323,611.

Specification of Letters Patent.

Patented Dec. 2, 1919.

Application filed July 12, 1913. Serial No. 778,735.

To all whom it may concern:

Be it known that I, JOHN REAM, a citizen of the United States, residing at Jacksonville, in the county of Duval and State of Florida, have invented new and useful Improvements in Dredging Apparatus, of which the following is a specification.

The present invention relates to dredging apparatus and has for its object to provide mechanism for dredging and at the same time distributing such dredged material in the form of levees or dikes on either or both sides of the line of operation, my improved apparatus being so designed as that the levees may be built in any desired width and of uniform height to the end that practically a finished levee results and the necessity for leveling, shaping and finishing is almost entirely done away with.

Furthermore, the dredger and levee builder which I shall describe in detail hereinafter is of such construction that a wide range of work may be taken care of without such frequent repositioning of the base or barge, if the dredge be a floating one, as is now necessary in many machines of this general type.

Other features of improvement will be brought out in the disclosure hereinafter and more fully described, and that which I regard as novel and of my invention will be particularly pointed out in the claims appended hereunto.

In order that the invention may be clear to those skilled in the art, the following description is to be taken in connection with the drawings accompanying the same, and in which one embodiment of my invention is illustrated.

40 In said drawings:

Figure 1 is a view in side elevation of my dredging apparatus, with so much of a supporting barge as will illustrate the manner of mounting the dredging apparatus.

45 Fig. 2 is a view in front elevation of the apparatus, showing two units, one of which (that on the left) is stripped of the digging instrumentalities to more clearly show the supporting pedestal and yoke.

50 Fig. 3 is a detail view of the mechanism for operating the swiveling pedestal and its supported parts.

Fig. 4 is a detail view of the folding conveyer frames.

55 Fig. 5 is a detail view of the digging buckets.

Fig. 6 is an enlarged detail view of the digging buckets and their supports.

Fig. 7 is an end view, partly in section, of the trough and distributing conveyers.

60 Figs. 8 and 9 are plan and side elevations respectively of the distributing conveyers.

Fig. 10 is a plan view of the supporting frame for the distributing conveyers.

Fig. 11 is a side view of the central conveyer support.

Fig. 12 is a detail of the pedestal and yoke.

Figs. 13 and 14 are sectional views on lines *a-a* and *b-b* respectively of Fig. 12.

70 Fig. 15 is a side view of the cradle.

Fig. 16 is a plan view of a bucket, the blank from which it is made being shown in dotted lines.

Referring to the drawings by numbers, 75 like numbers indicating like parts in the several views, 10 denotes a suitable base on which the operative parts of the machine are supported, the base in the present instance being a barge which may be readily 80 moved from place to place in water of comparatively shallow depth.

85 Mounted on the barge 10 is a main support for the digging and elevating instrumentalities consisting of a post or pedestal 11 pivotally mounted at its lower end in suitable bearings on the deck of the barge, said post 11 having at its upper end a yoke 12 and being provided at its top with a journal or pivot which rotates in a bearing in a 90 frame 13 suitably supported from and guyed to the barge or other base.

95 The yoke 12 is preferably formed of continuous pieces of angle iron, as shown in Figs. 2, 12 and 13, two U-shaped angle irons 14, being assembled as shown, and seated in said angle irons are T-rails 15, the whole being bolted together so as to form an absolutely rigid, although relatively light, structure.

100 Where this yoke is secured to the pedestal I preferably, as best shown in Fig. 12, continue the inner T-rail 15 across the top of the pedestal as at 16, and extend the lower ends of the built-up yoke beam downwardly, 105 as at 17, about the pedestal to which it is bolted or otherwise suitably secured, the upper end of the pedestal being preferably squared, or so designed in cross section, as shown at 18 Fig. 14, as that it fits closely 110 and securely in the receiving pocket thus formed at the lower end of the yoke..

The said pedestal is provided near its lower end with means for moving it angularly, said means comprising the frame 19 secured to the pedestal 11 and having at its outer end the drive rack 20 of arc shape. The said rack 20 is engaged by idler pinions 21 mounted on shafts journaled in a suitable framework 22, one of said pinion shafts, as 23, being driven from a suitable prime motor. Each of said pinions has a clutch face adapted to be engaged by a clutch 24 splined to the pinion shafts and having suitable operating levers. It will be obvious that when the clutch 24 on the power shaft 23 is engaged with the clutch face of pinion 21, said pinion 21 will be rotated, the rack 20 and its frame swung, and the pedestal 11 moved angularly relative to its support. In order that an opposite or reverse movement may be given to the pedestal I preferably provide a gear 25 on the power shaft 23, which engages a drive pinion 26 on the other pinion shaft so as to drive pinion 21 in an opposite direction from its fellow, and give a reverse movement to pedestal 11.

Pivottally mounted in the yoke 12 is a cradle or bed 27 for the boom which carries the digging chain, said cradle being provided with anti-friction bearings 28 on which rests the boom 29 which may be of any suitable construction. The boom 29 has a slide plate 29^a bolted to its framework, the ends 29^b of which are turned downwardly, as shown in Figs. 1 and 15 to limit the traverse of the boom, and clamping plates 29^c are secured to the cradle, which engage the plate 29^a and hold the boom to its seat. Said boom is provided at either end with sprockets 30 over which the bucket chain 31 travels, this chain being provided with buckets 32 for digging, scooping, and elevating the material. The boom 29 is provided at one end with a slack takeup 33 of any suitable design so that the slack of the chain may be cared for, and near its upper end it has any suitable motor 34, conventionally shown as an electric motor, which, by suitable gearing, best shown in Fig. 1, drives the drum or sprocket 30 at the upper end of the boom to actuate the chain.

It will be seen that the boom with its bucket chain is so supported in the cradle carried by the pedestal that it may be swung angularly through a wide range when the pedestal 11 is moved through the mechanism just described, and in order that the boom may be raised and lowered to suit the needs of the work I preferably counter-weight it by means of weights suspended from a hawser passing over suitable sheaves 36 on the frame-work, with the bight of the hawser looped over sheaves 37 on the boom, as shown in Fig. 1. A haul rope 38 passing around pulleys 39 on the boom extends

rearwardly over pulleys 40 on the frame, the ends passing to any suitable take-up device or winding drum (not shown) on the deck of the barge, so that when draft is applied to this haul rope the boom will slide readily upward in the cradle, the counterbalancing weights and the anti-friction rollers carried by the cradle rendering the raising and lowering of the boom a comparatively easy matter. 75

In order that the boom may be maintained at its working angle in proper position for operating the digging buckets, its outer end is suspended from a swinging boom 41 adjustably held by block and tackle 42, and by means of a block and tackle 43, coupled by the bail 44 to the bucket boom, suspends its outer working end in any desired position; a haul rope 45 being provided by means of which the bucket boom may be raised and lowered to accommodate itself to different depths and to different angles at which it may be necessary to work. 80

With this construction it will be obvious that a wide range is given to the bucket boom, for it may be placed at an angle where it will work close to the base or barge, and this angle may be altered as the work progresses until it is operating at its extreme range of movement in front of the barge. 85 Since it is mounted on a swiveling pedestal it may be swung through a wide arc and work in any of its angular positions, thus providing for a wide range of work. 90

The buckets or diggers are formed individually and hinged together, as shown in Fig. 5, said buckets being formed of a single blank, as shown in dotted lines Fig. 16, the side walls 46 and end walls 47 being bent up and riveted together in any suitable manner 100 at the corners. Preferably the bottoms 48 of the buckets will be provided with openings to permit the escape of water from the material being dredged and to prevent suction or vacuum when dumping. The rear wall 47 of the buckets is provided with a removable digger blade 49 which is riveted in a seat 50 formed in said rear wall 47, as shown in Figs. 5 and 6, the upper edge of the digger blade 49 being curved, as shown in 105 Fig. 6, and the blade being concaved on its inner face to facilitate its entering the ground or material being scooped into the buckets. I preferably sharpen the side walls 46 at their upper edges with an inward bevel as shown, so as to give a cutting edge to them and facilitate entrance of the buckets into the soil, and cutting of any embedded fibrous material. 110

Each bucket is provided with supporting 115 rollers 51 which run upon suitable track-way 52 on the boom, as shown in Fig. 6.

In order to insure the buckets on the lower run of the bucket chain being properly guided so that slack in the bucket chain will 120

not strike and interfere with the other parts of the apparatus, I provide the guide-ways 53, the one at the upper end being relatively short so as to hold the chain away 5 from the conveying mechanism after the buckets have dumped, while the lower guide is relatively long, and picks up the chain as soon as it has swung below the cradle and other projecting parts which it is necessary 10 to the lower run of the bucket chain should clear. The said guides have flaring mouths, as shown, to permit the rollers 51 of the buckets to leave and enter the guides readily, and to allow for variations in the line of 15 travel of the bucket chain.

In rear of the supporting standards I provide a conveyer frame 54 above which is mounted a relatively wide trough having a high sloping rear side 55 preferably supported from the frame 13, as shown in Fig. 1, and a lower sloping front side 56, a conveyer 57 having upstanding sides which lap and embrace the sides 55 and 56 of the trough, forming the bottom of this trough. 20 The width of said trough is designed to be such that it will receive material discharged by the buckets on the bucket boom at any angle at which the boom may be working, so that the buckets may work through their 25 entire longitudinal and angular range and yet discharge the material into the trough, in which, owing to the inclined sides, the material will fall to the traveling conveyer 57 and be carried in one or the other direction at right angles to the dredge or line of dredging.

The traveling conveyer is supported on suitable track ways 58, as shown in Fig. 7, the supporting wheels 59 mounted on suitable stub shafts on the conveyer running 40 along the track-way. A sprocket shaft 60 having suitable sprockets 61 engages the conveyer to drive it, these sprocket wheels being driven in any suitable manner from a 45 proper source of power, as, for example, the motor 61^a, drive chain 61^b, and sprocket or pulley 61^c, conventionally shown in Fig. 2; and, by drive chains 62, 63, the power from the shaft 60 is carried to the outwardly extending distributing conveyers, presently to 50 be described, and all as shown in Fig. 7. In order that the conveyer 57 may be properly supported at all points, and not buckle under its load, I provide a central supporting arch 55 64, as best shown in Fig. 7, bolted to the conveyer frame proper, and having a series of overlapped, closely arranged, supporting rollers 65 which are placed centrally beneath the conveyer 57, and serve to support 60 said conveyer and its load in proper position.

The supporting frame 54 for the traveling conveyer just described is secured to suitable supports 64^a by means of a sliding 65 pivot, as shown in Figs. 2 and 4, so that the

rear end of the conveyer frame and the trough conveyer 57 may be raised and lowered to move the conveyer frame and conveyer 57 from the substantially horizontal working position to the inclined position 70 shown in Fig. 4, and preferably I provide a counterbalancing weight 64^b, see Fig. 4 for this sliding pivotal connection between the conveyer frame and the slideways on the supports 64^a. 75

The said trough is intended to be of a length substantially equal or little more than the width of the dredge or dredging operation. At one or both ends of the trough is the distributer or levee-building 80 device, which comprises a series of distributing conveyers, the inner one 66 of which receives the material which falls from the trough conveyer 57 and carries this discharged material outwardly over the point 85 where the levee is to be built.

The levee building conveyers are all alike, except as to dimensions, and comprise sprocket shafts 67 which drive the slat conveyers 68 which are preferably of the overlapped type shown in Fig. 9. These slat conveyers 68 have no retaining sides so that part of the dredged material will readily fall from them and be deposited below, suitable guide wings 69 being provided to direct 90 the material outwardly away from the sprockets, sprocket chains, and drive connections. The distributing conveyers are mounted on supporting frames 70 of gradually decreasing widths, as shown in Fig. 7, 100 and are provided with supporting wheels 71 which run on tracks 72, as shown in Figs. 7, 8 and 9.

The distributing conveyers are preferably sustained by means of a haul rope 72^a which 105 passes over a suitable sheave on the upright 72^b, and thus to a guide pulley on the frame from which the haul rope is led to any suitable take-up or winding device (not shown) for raising and lowering the distributing 110 conveyer.

It will be seen that as the mass of material is delivered from the trough by the trough conveyer 57 to the inner distributing conveyer 66, it will be moved forward and a certain proportion of it will fall from the sides of the conveyer 66 to the levee below, the speed of movement of the conveyer being such that it will be distributed in a practically even stream on either side throughout 115 the length of the conveyer.

Adjacent said conveyer 66 is a second conveyer of similar construction although of less width than the first conveyer and arranged on a somewhat lower level so that the 120 conveyer 66 will dump its load onto a second conveyer 73, and it in turn will distribute the material in even lines to form the levee. The second conveyer 73 in turn delivers to a third conveyer, which is still narrower, 125 130

and the even distribution of the material continues until it has all been distributed, and such distribution, owing to the narrowing or successively decreasing widths of the 5 conveyers as they progress outwardly will be regular and result in an evenly built levee.

In the practical carrying out of my invention I contemplate mounting two or more digging and conveying instrumentalities on 10 a barge, as shown in Fig. 2, so that as the apparatus proceeds the digging may be uniformly carried on through a wide range, and levees built simultaneously on either side of the line of dredging. As shown in Fig. 2 15 the two digging instrumentalities and the conveying devices will be identical, and the conveyers and distributors will extend outboard from either side of the barge or support, so as to deliver and distribute the 20 dredged material uniformly on each side, the trough conveyers and the distributing conveyers moving in opposite directions so as to properly convey the material.

By reason of the wide range of action 25 which is given to the bucket boom it will be seen that the digging instrumentalities may work at different angles, and at different distances from the barge, and yet the conveyers which receive the material will carry it and 30 distribute it uniformly and regularly as the barge is advanced.

It is obvious, of course, that the number 35 of conveyers and their relative widths and lengths to accomplish this distribution may be varied so as to meet the needs of each dredger, for the character of the soil varies in different localities and proportions suitable for one operation would perhaps not be proper for operations in different soils; 40 and while I have shown a particular construction in this disclosure, it will be understood that different mechanical expedients other than those shown may be substituted to attain the results aimed at without de- 45 parting from the spirit of my invention.

I claim:-

1. In a dredging and distributing apparatus and in combination, a receiving trough for dredged material having an open top and bottom, means angularly movable relative to said trough for depositing dredged material therein, an endless conveyer disposed exteriorly of said trough and provided with upturned sides to provide a movable trough bottom, and supplementary conveying and distributing means of progressively narrower width to which said endless conveyer delivers.

2. In a dredging and distributing apparatus and in combination, a hinged vertically 60 swinging pivotally mounted dredging boom,

a trough for dredged material wedge shaped in cross section and open at top and bottom, means angularly adjustable relative to said trough for depositing dredged material in 65 said trough, an endless conveyer disposed exteriorly of said trough and forming a movable bottom therefor, the sides of said conveyer being upturned to embrace the open bottom of said trough, and supplementary conveying and distributing means to which said endless conveyer delivers.

3. In a dredging apparatus and in combination, a receiving trough for dredged material, means for depositing dredged material in said trough, an endless conveyer for the material deposited in said trough hinged at one end to a suitable support, a slide way to guide the opposite end of said endless conveyer as it is raised or lowered, 80 a supplementary conveyer to receive the material from said endless conveyer and hinged at one end to a suitable support, and means for raising and lowering said supplementary conveyer to move it from an operative to an 85 inoperative position.

4. In a dredging and distributing apparatus and in combination, a receiving trough for dredged material, an endless traveling conveyer forming the bottom of said trough, 90 means to deposit dredged material in said trough and upon said conveyer, and supplementary conveying and distributing means comprising a plurality of overlapping conveyers of successively decreasing width to 95 receive the material from said first named endless conveyer and from one another and effect a side delivery of the same throughout the length thereof.

5. In a dredging and distributing apparatus and in combination, a receiving trough for dredged material having an open top and bottom, means for delivering dredged material to said trough, an endless conveyer forming the bottom of said trough, a support for said conveyer, a pivotal connection between one end of said conveyer and said support, and a supplementary conveying and distributing means comprising a plurality of endless conveyers pivotally mounted relative to said conveyer to permit said supplementary conveying and distributing means to be swung from an operative to an 105 inoperative position.

In testimony whereof I have hereunto set 110 my hand in presence of two subscribing witnesses.

JOHN REAM.
